DIE CASTING APPARATUS

Harry E. Pouell, Logansport, Ind., assignor, by direct and mesne assignments, of one-sixth to George A. Gust and one-sixth to Robert G. Irish, both of Fort Wayne, Ind., and one-third to Mary M. Fouch, Kokomo, Ind.

Filed June 9, 1961, Ser. No. 116,120
21 Claims. (Cl. 22—68)

The present invention relates to an improved die casting apparatus for manufacturing wheel balance weights and the like.

Wheel balance weights as attached to the rims of automobile wheels conventionally consist of two parts, namely, a U-shaped clip fabricated of strip steel stock and a lead body having imbedded therein one leg of the clip. These balance weights have been manufactured for many years by means of equipment operated under different degrees of automation; however, to the best of my knowledge and belief, no prior art machine has successfully, for mass production purposes, manufactured wheel balance weights by apparatus which are operated completely automatically.

It is, therefore, an object of this invention to provide die casting apparatus for manufacturing wheel balance weights and the like which may be operated automatically for providing a finished balance weight free of flash and residue sprue and ready for attachment to the rim of an automobile wheel.

It is another object of this invention to provide mechanism whereby U-shaped clips may be fed to a die automatically in operations which are sequential and do not require manual attendance.

It is another object of this invention to provide die casting apparatus wherein the sprue developed in casting a wheel balance weight may be automatically sheared from the finished weight in such a manner as to require no further finishing before the weight is applied to a wheel or the like.

It is still another object of this invention to provide a unique arrangement of casting molds which may be operated in such a manner as to provide a single die cavity during the casting of a wheel balance weight and thereafter be separated in order to eject mechanically the finished weight from the mold. Additionally, it is an object to provide means for closing the mold as a first step, feeding a U-shaped clip to the mold prior to injection of molten metal thereinto, injecting molten metal into the die cavity, thereafter opening the mold, shearing the sprue off the finished weight, and then ejecting the weight from the apparatus in finished form. As a further object, automatic means are provided for effecting all of these operations in rapid sequence.

As a still further object of this invention, numerous, unique subcombinations and assemblies are provided which may be used in die casting apparatus which is operable either fully automatically or semiautomatically.

Further objects will become apparent as the description proceeds.

The above-mentioned and other features and objects of this invention and the manner of attaining them will become more apparent and the invention itself will be best understood by reference to the following description of an embodiment of the invention taken in conjunction with the accompanying drawings, wherein:

In the drawings:

FIG. 1 is a perspective illustration of a typical, conventional wheel balance weight;

FIG. 2 is a sectional illustration taken substantially along section line 2—2 of FIG. 1;

FIG. 3 is a rear perspective illustration, partially broken away and sectioned for clarity, of an embodiment of the present invention;

2

FIG. 4 is a front perspective illustration of the embodiment of FIG. 3, also partially broken away and sectioned for clarity of illustration;

FIG. 5 is a top plan view of the apparatus of FIGS. 3 and 4, partially sectioned and broken away for clarity of illustration;

FIG. 6 is a perspective view partially sectioned and broken away of the various mold sections which are operable to provide a die cavity;

FIG. 7 is a side view of the rear mold sections of FIG. 6 and the sliding support therefor;

FIG. 8 is a rear view of the subassembly of FIG. 7 taken substantially along the section line 8—8;

FIG. 9 is a top plan view of the mold sections and mounting apparatus shown partly sectioned horizontally to reveal cooling water cavities;

FIG. 10 is a cross-sectional illustration taken substantially along section line 10—10 of FIG. 9;

FIG. 11 is a cross-sectional illustration taken substantially along section 11—11 of FIG. 9 and showing the water passage for cooling the movable die member;

FIG. 12 is a fragmentary top plan view of the movable die sections, the carrier therefor, cam-actuating devices and a portion of the mechanism for feeding clips to the die sections, this figure being somewhat enlarged to show various elements more clearly;

FIG. 13 is a cross-sectional illustration taken substantially along the section line 13—13 of FIG. 12;

FIG. 14 is a cross-sectional illustration taken substantially along section line 14—14 of FIG. 12;

FIG. 15 is a cross-sectional illustration taken substantially along section line 15—15 of FIG. 12, this figure illustrating one of the operative positions of the cross-slide;

FIG. 16 is a sectional illustration taken substantially long the section line 16—16 of FIG. 12 partially broken away for clarity of illustration and showing the means for feeding a U-shaped clip to the die cavity, the mechanism being shown in actuated position whereby a clip is being fed to the die cavity and molten lead is also being injected into the cavity;

FIG. 17 is a fragmentary sectional view similar to FIG. 16 but showing the position of the various parts just prior to the injection of molten lead into the die cavity;

FIG. 18 is a fragmentary view similar to FIGS. 16 and 17 but showing the clip-plunger retracted and the sprue-shearing device partially actuated;

FIG. 19 is a sectional illustration similar to FIG. 18 showing the clip-plunger retracted and the sprue-shearing device fully actuated to sever the sprue and also to eject the finished balance weight from the apparatus;

FIGS. 20a, 20b, 20c and 20d are diagrammatic illustrations of the cross-slide mechanism which cooperates with the clip plunger to feed clips to the die cavity, these various views showing the mechanism in different operative positions;

FIG. 20e is a side view of the mechanism of FIGS. 20a through 20d inclusive illustrating certain of the camming means used in operating the cross-slide;

FIG. 21 is a perspective illustration partially broken away and sectioned of a portion of the clip-feeding mechanism;

FIG. 22 is a cross-sectional illustration taken substantially along section line 22—22 of FIG. 21;

FIG. 23 is a cross-sectional illustration taken substantially along section line 23—23 of FIG. 21;

FIG. 24 is a top plan view of the horizontal and inclined feed-rails, partially broken away and sectioned, of the mechanism of FIG. 21;

FIG. 25 is a cross-sectional illustration taken substantially along section line 25—25 of FIG. 24;

FIG. 26 is a partial, front perspective view of the apparatus showing the clip-feeding assembly coupled to the die-casting mechanism;

FIG. 27 is a front view of the clip-plunger assembly assembled to the distal, feeding end of the mechanism of FIG. 21;

FIG. 28 is a partial top plan view of the detent device used in the clip-feeding mechanism of FIG. 21, this detent device being used for feeding U-shaped clips in unison with protractile rail movement;

FIG. 29 is a partial side elevation of the mechanism shown in FIG. 28 showing the back stop which is engaged by the clips during retractile movement of the horizontal, clip-conveying rail;

FIG. 30 is a side elevation of the inclined feed rail which forms a portion of a clip-feeding mechanism partially shown in FIG. 21;

FIG. 30a is a fragmentary side elevation of the inclined feed rail of FIG. 30 showing the clip-derailing device;

FIG. 30b is a top view of FIG. 30a;

FIG. 31 is a cross-sectional illustration taken substantially along section line 31—31 of FIG. 30;

FIG. 32 is a sectional illustration taken substantially along section line 32—32 of FIG. 30;

FIG. 33 is a rear side view of the assembly of FIG. 30;

FIG. 34 is a perspective illustration of the vibrating mechanism which feeds automatically clips to the inclined rail of FIG. 30;

FIG. 35 is a side elevation shown partially in cross-section taken along the section line 35—35 of FIG. 34;

FIG. 36 is a horizontal section taken substantially along section line 36—36 of FIG. 35;

FIG. 37 is a side view of the barrel cam;

FIG. 38 is a cross-sectional view taken substantially along section line 38—38 of FIG. 37;

FIG. 39 is a cross-sectional view taken substantially along section line 39—39 of FIG. 37;

FIG. 40 is a diagrammatic development of the periphery of the barrel cam of FIG. 37 showing the relative arrangement of the various cam grooves;

FIG. 41 is a diagrammatic planar development of the camming groove in the end of the barrel cam of FIG. 37 showing the relationship of this camming groove with the various grooves in the view of FIG. 40; and

FIG. 42 is a diagrammatic illustration of the entire apparatus of this invention with certain parts being removed and sectioned for clarity of illustration.

Referring to the drawings, and more particularly to FIGS. 1 and 2, a wheel balance weight of the type fabricated by the apparatus of this invention is conventional and comprises a U-shaped clip 50 fabricated of sheet or strip steel stock having one leg imbedded in an arcuately shaped lead body 51. The apparatus of this invention not only molds the lead body 51 but also positions the clip 50 properly so that the lead body can be molded around the one clip leg. The apparatus as hereinafter described is particularly suited for fabricating this wheel balance weight automatically.

Referring to FIGS. 3, 4, 5, 6, 9, 10 and 42, the apparatus is shown as comprising a stationary frame or support 52 having two upstanding sides 54 which are spaced apart and parallel as shown more clearly in FIG. 8. On the upper edges of these two plates 54 are mounted a pair of inwardly facing gib rails 56 which have slidably mounted for reciprocation thereon a plate or carrier 58 (FIGS. 5, 6, 8, 9, 10, 11, 12 and 42).

Mounted on and extending between the stationary side plates 54 is another stationary, flat plate 60 which is set at an angle of 45° with the vertical so as to be inclined as shown in FIGS. 3, 6 and 7. FIG. 8 shows a rear view of this plate. Referring more specifically to FIGS. 6 and 7, this plate 60 has mounted on the upper, horizontal end surface 62 a gib block 64 which is elongated and which extends forwardly over the upper inclined surface 66 of the inclined plate 60. This overhanging portion is indi-

cated by the reference numeral 68 which provides an elongated exposed corner 70 which, as will be described hereinafter, serves as a gib or way on which rear mold sections 72 and 74 slide.

These rear mold sections 72 and 74, shown more clearly in FIGS. 6, 7, 9, 12 and 16, constitute halves of a single die block which forms one-half of the die cavity in which the lead weight 51 is molded. The mold sections 72 and 74 are identically formed but are in reverse configuration such that when they are abutted together, a single die block is formed. As seen in FIGS. 6 and 7, the rear edges of these two mold sections 72 and 74 are provided with a right-angle, longitudinally extending groove 76, each of the grooves 76 fitting over the corner 70 provided by the gib block 64. A bar 78 bolted to the inclined plate 60 extends along the upper surface 66 of the latter parallel with the corner 70 and is engaged by the lower edges 80 of the two mold sections 72 and 74 as shown more clearly in FIGS. 6 and 7. The combination of the bar 78 and the corner 70 forms a way in which the two mold sections 72 and 74 may be reciprocated alternatively into and out of engagement with each other.

The facing ends 82 and 84 of the mold sections 72 and 74, respectively, (FIGS. 6 and 12), are machined perfectly flat and complementary so that when the two sections 72 and 74 are abutted at the surfaces 82 and 84, a single, unitary die block having a cavity recess 86 is provided. The two mold sections 72 and 74 are of uniform thickness and are provided in the facing ends 82 and 84 thereof with halves 88 (FIG. 6) of a sprue hole. When the surfaces 82 and 84 are abutted against each other, the two halves 88 register with each other to form a single, elongated passage which communicates with the cavity recess 86. The sprue halves 88 are shown as forming a single passage in FIGS. 16 and 17.

Straddling the surfaces 82 and 84 of the mold sections when the surfaces are abutted is an upstanding lip 90 (FIG. 6) on each of the mold sections 72 and 74. These lips 90 constitute halves of a clip-receiving portion of the mold sections when the latter are abutted, the cross-section of the lip sections 90 being shaped the same as the inner cross-sectional contour of the clip 50 as shown in FIGS. 1 and 2. The configuration of this lip 90 and the manner in which the clip 50 fits thereover is shown more clearly in FIGS. 16, 17, 18 and 19.

These lips 90 are machined into the mold sections 72 and 74, and when abutted, the total lip length corresponds almost precisely with the length of a single clip 50 (FIGS. 1 and 2). At the opposite ends of the joined lips, shoulders 91 extend transversely and are spaced apart a clip length to receive therebetween a clip 50 with only negligible clearance. It should be noted that the clip-receiving portion as constituted by the two lips 90 is positioned in substantially the exact center of the mold sections 72 and 74 and immediately adjacent to the cavity recess 86 so that a clip placed over the clip-receiving portion has one leg entered into the recess 86. This will be explained more fully later in the description.

The gib block 64 immediately to the rear of the two mold sections 72 and 74 is provided with a rectangular cut-out 92 (FIG. 6) for a purpose which will be explained more fully in the following. This cut-out 92 has a width equal to the length of the clip-receiving portion 90 and a clip 50. Also, the rear surface 94 of the cut-out is slanted at an angle of 45° in line with the surface 66 of the inclined plate 60. This is best illustrated in FIGS. 16, 17, 18, and 19.

On the opposite ends of the two mold sections 72 and 74 are provided two rollers 96 and 98, respectively (FIGS. 5, 6, 8, 9 and 12), which fit into two camming grooves 100 and 102 provided in the under surface of the carriage plate 58. These grooves 100 and 102 are identical in shape to each other but are oppositely shaped so as to move the mold sections 72 and 74 inwardly and outwardly, respectively, in response to reciprocation of the carrier

plate 58. As shown more clearly in FIG. 12, the grooves 100 and 102 have three straight portions 104, 106 and 108 which extend parallel to the direction of the sliding movement of the carrier plate 58 and two inclined portions 110 and 112 intermediate thereof. Considering FIGS. 5, 6 and 12, with the carrier plate 58 fully retracted to the illustrated position, the mold sections 72 and 74 will be fully and completely separated as shown. As the carrier plate 58 is protracted, the mold sections are progressively moved inwardly by means of the inclined surfaces 110 and 112 until the surfaces 82 and 84 fully abut when the rollers 96 and 98 enter the straight portions 108 of the two grooves 100 and 102, respectively. Thus, when the carrier plate 58 is fully protracted, the mold sections 72 and 74 are abutted together to provide a single, stationary die block. When fully retracted, the carrier plate 58 separates the mold sections.

Mounted on the edge 114 of the carrier plate 58 is a front die block 116 as shown in FIGS. 5, 6, 9, 10, 11, 12 and 16 through 19 inclusive. In FIGS. 5 and 19, the die block 116 is shown as having an elongated, arcuately shaped recess 118 which overlies and mates with the recess 86 in the two mold sections 72 and 74 when the latter are abutted. Since the die block 116 is carried by the carrier plate 58, protractile movement of the latter results in closure of the two mold sections 72, 74 and the die block 116 onto these mold sections. As explained earlier, the two mold sections 72 and 74 when closed form a single, stationary die block. The die block 116 is movable by virtue of the fact that it is fastened to the carrier plate 58 and is provided with surfaces surrounding the cavity recess 118 which are engageable in sealing relation with companion surfaces on the stationary die 72, 74. When the dies are fully closed, the recesses 118 and 86 surround a die cavity having the shape of the lead body of FIG. 1.

As shown more clearly in FIG. 5, the rear edge 120 of the die block 116 is notched out so as to fit snugly over a clip 50 when the latter is placed over the clip-receiving lips 90 of the mold sections 72, 74. This indentation 120 is so sized and shaped as to engage and seal over the clip 50 when the latter is inserted into the die cavity to prevent molten lead from escaping from the die cavity.

Referring to FIGS. 8, 9, 10 and 11, the carrier plate 58 is provided with internal cavities 122 by which a cooling flow of water may be introduced at 124 and exhausted at 126. Communicating with the water cavity 122 in the carrier plate is an elongated water cavity 128 in the die block 116 (FIG. 11). Thus, the water which circulates between the two pipes 124 and 126 is circulated through the water cavities 122 in the carrier plate 58 and also through the die block 116 for cooling the latter.

Clip-plunger mechanism

The clip-plunger mechanism is shown in FIGS. 3, 4, 5, 6, 7, 16, 17, 18, 19, 21 and others. Referring more specifically to FIGS. 6, 16 and 21, an elongated, rectangular bar of steel 130 is of a cross-sectional size and shape as to fit snugly and slidably into the rectangular cutout 92 (FIG. 6) in the gib block 64. This bar or plunger 130 is mounted to reciprocate vertically into and out of the cutout 92 (FIG. 6) by means of an upright guide block 132 as seen in FIGS. 3, 4, 16 and 21. This guide block 132 is mounted securely on the gib plate 64 (FIG. 6). The plunger 130 is yieldably urged vertically upwardly by means of a tension spring 134 connected at its lower end to a pin 136 fastened to the plunger 130 and at its upper end to a stationary post 138 which is fastened to the guide block 132. A rubber cushion 140 is fitted between the upper end of the plunger 130 and the guide block to cushion the impact of the plunger 130 with the upper end of the guide block 132.

The lower end of the plunger 130 is provided with a U-shaped notch or groove 140 (FIGS. 6, 18). The shape and size of this U-shaped groove 140 is made to fit precisely the outside U-shape of an individual clip 50 (FIG. 1).

The fit between the clip 50 and the U-shaped recess is shown clearly in FIGS. 16, 17, 18 and 19.

5 A pair of bar magnets 142 are imbedded or otherwise secured in the lower end of the plunger 130 so as to have the ends thereof terminate contiguously with the recess 140 (FIGS. 16, 17, 18, 19 and 21). By means of these magnets 142 which form a part of the plunger 130 assembly, steel clips 50 are held in the recess 140 as shown in the various figures and especially FIG. 21.

10 A clip 50 inserted into the plunger 130 when the latter is in its elevated position as shown in FIGS. 6 and 21 is held in place by the magnets 142 whereby the plunger 130 may be lowered into the cutout 92 (FIG. 6) to position the clip over the lips 90 of the mold sections 72 and 74 when the latter are closed. This positioning by the plunger 130 is shown in FIGS. 16 and 17.

Plunger-depressor mechanism

20 The plunger-depressor mechanism is clearly illustrated in FIGS. 3, 4, 5, 12 and 20. It comprises a gib block 144 mounted on the carrier 58 so as to provide a transverse way in which a block or cross-slide 146 is received. The way provided by the gib block 144 extends in a direction parallel to the direction of movement of the two mold sections 72 and 74 and at an angle of 90° with respect to the direction of reciprocation of the carrier plate 58.

25 To the inner end of the cross-slide 146 is attached a depressor cam 148 having an inclined cam surface 150 on the rear end thereof which engages the upper surface of the roller 152 mounted on the side of the plunger 130.

30 As shown in FIG. 16, the depressor cam 148 is provided with a spring-biased plunger 154 which is yieldably urged against the roller 152 when the depressor cam 148 is operatively engaged with the plunger 130. When the carrier

35 plate 58 is protracted from the position of FIG. 3, the cam surface 150 will force progressively the roller 152, hence the plunger 130, downwardly until the plunger 154 rides over and onto the roller 152 to urge yieldably the plunger 130 downwardly to the position illustrated in FIG. 16. It will also be seen that when the depressor cam 148 is withdrawn from the roller 152, the plunger 130 will move upwardly under the influence of the tension spring 134.

40 As shown in FIG. 12, a tension spring 156 connected between the cross-slide 146 and the gib block 144 yieldably urges the cross-slide 146 to the position shown (FIG. 12). In this position, the depressor cam 148 is engageable with the plunger roller 152.

45 As shown more clearly in FIGS. 3, 12 and 20, protractile movement of the carrier plate 58 moves the outer end 158 of the cross-slide 146 onto an upwardly biased plunger 160 which is mounted on the upper end of a releasing cam 162. The dashed line position 164 (FIG. 12) of the cross-slide 146 as well as the full line view in FIG. 55 20b illustrate the position of the cross-slide relative to the plunger 160 when the carrier plate 58 has fully protracted to close the mold cavity.

50 In the underside of the cross-slide 146 adjacent to the outer end 158 is a transverse groove 166 which is inclined as shown in FIG. 13 to depress the plunger 160 as the cross-slide 146 moves forwardly. This same end of the cross-slide 146 is also provided with an angular groove 168 (FIGS. 12 and 13) which merges with the right-hand end (FIG. 12) of the groove 166. This slanted groove 65 168 is of uniform depth, as shown in FIG. 13.

55 The releasing cam 162 is fastened to a reciprocating bar 170 (FIG. 12) which is mounted on the side plate 54 to move horizontally from front to rear of the machine. In other words, the bar 170 is mounted for sliding movement in a direction parallel to the movement of the carrier plate 58.

60 The operation of the cross-slide 146 will now be described. The starting position is as illustrated in FIGS. 3, 12 and 20a. In the first motion, the carrier plate 58 protracts to close the mold sections 72, 74, 116. This

results in carrying the cross-slide 146 forwardly to the position F2 of FIG. 20b at which position the plunger 130 is fully depressed. The groove 166 in the cross-slide 146 has just entered over the plunger 160.

In the next cycle of movement, the releasing cam 162 is moved rearwardly to the position F3 as shown in FIG. 20c until the plunger 160 has entered the region where the two grooves 166 and 168 merge.

Following this, the releasing cam 160 is moved forwardly to the position of F4 of FIG. 20d whereupon the plunger 160 has engaged the slanted groove 168 thereby forcing the cross-slide transversely away from the plunger 130 and the roller 152. In this position of FIG. 20d, two ball detents 172 which are carried by the cross-slide 146 (FIGS. 14 and 15) are spring-biased downwardly to engage two companion sockets 174 in the gib block 144. By means of these spring-urged balls 172, the cross-slide 146 is held in the position of FIG. 20d while the carrier plate 58 retracts to the dashed line position (FIG. 20d). In this latter position, a roller 176 mounted on the outer end 158 of the cross-slide 146 as shown in FIG. 20e engages a cam surface 178 on a camming block 180 mounted on the side wall 54. Continued retraction of the carrier plate 58 carries the cross-slide 146 rearwardly against the camming surface 178 which forces the cross-slide 146 transversely (or upwardly as viewed in FIG. 20d) thereby disengaging the ball detents 172 from their companion sockets 174 (FIG. 15). Once these detents are disengaged, the spring 156 (FIG. 12) pulls the cross-slide 146 transversely to the position shown in FIG. 12. Thus a complete cycle of cross-slide operation has been given.

Cooling system

Water cooling of the carrier plate 58 as well as the movable die block 116 has already been described. The rear mold sections 72 and 74 are cooled by thermal contact with the inclined plate 60 and the gib block 64. In the inclined plate 60 is provided two water cavities 182 which are connected together by a passage 184 which passes upwardly through the gib block 64 as shown in FIGS. 7 and 8. Water introduced at the inlet 184 may thereby be circulated upwardly through the first cavity 182, through the passage 184, backwardly through the second cavity 182 and outwardly from the exhaust port 186. By this means, the mold sections 72 and 74 are kept cool throughout operation of the machine.

Sprue-shearing device

The sprue-shearing device is illustrated in detail in FIGS. 16-19 inclusive, and as shown in FIGS. 3 and 5 is mounted on the gib block 64 immediately to the rear of the plunger guide block 132. This sprue-shearing device is composed of a double acting air cylinder 186 which is bolted to both the gib block 64 and guide block 132. The cylinder 186 is mounted on an angle in alignment with the slanted surface 94 of the gib block 64 and the surface 66 of the inclined plate 60. As shown in FIG. 16, a piston 188 mounted in the cylinder 186 is provided with a hollow piston rod 190 which carries on the lower end thereof a shear head 192. This shear head 192 is a rectangular block of steel provided with a V-notch 194 in the lower end thereof. This V-notch terminates in the upper portion of the shear head 192 in a horizontal knife edge 196 for a purpose which will be explained in more detail hereinafter. Lower edge 198 of the shear head is formed with a sharp right-angle corner also for a purpose which will be explained more fully hereinafter.

As shown in FIG. 6, the plunger 130 is provided with a notch 200 on the rear side thereof, and reference to FIGS. 16 and 17 will reveal that this notch 200 provides a tooth which is engaged by the V-notch 194 in the lower end of the shear head 192. By this means, the shear head latches the plunger 130 in its lowermost position, as illustrated in FIGS. 16 and 17.

A plunger 202 is reciprocably mounted inside the piston

rod 190 and is biased outwardly by a compression spring 204. The purpose of this will be explained more fully hereinafter.

At this point it is important to note that when the piston 188 is fully protracted (downward position), the shear head 192 is slidably moved across the inclined surface 94, 66 in the space normally occupied by the mold sections 72 and 74. Obviously, before the shear head 192 can protract, the mold sections 72 and 74 must be separated to the position as shown in FIG. 6.

The shear head 192 is positioned in exact registry with the sprue hole 88 when the mold sections 72, 74 are closed, such that when the mold sections 72, 74 are separated, advancing of the shear head 192 will intercept the space formerly occupied by the sprue hole 88. By this means, a sprue formed by the sprue hole 88 may be severed by the shear head 192.

Also of importance is the fact that the thickness of the sprue head 192 is substantially equal to the thickness dimension of the two mold sections 72 and 74.

Air pressure introduced to the inlet port 206 of the air cylinder 186 serves to protract piston 188. Similarly, air pressure introduced into the port 208 serves to retract the piston 188.

As shown more clearly in FIGS. 16-19 inclusive, a conduit or gate 210 by which molten metal is conducted to the sprue hole 88 is fixedly mounted with respect to the inclined plate 60. An elongated opening 212 in the inclined plate 60 receives the conduit 210 which communicates at its lower end with the lead pot 214 (FIG. 3). The upper end of this conduit 210 has an opening 216 which precisely registers with the sprue hole 88 in the two mold sections 72 and 74 when the latter are closed onto each other. Also as will be seen in FIGS. 16-19 inclusive, the upper end 218 of the conduit 210 is terminated flush with the surface 66 of inclined plate 60.

It will now be seen that as the shear head 192 is protracted, it will slide over the end 218 in intimate contact therewith as clearly shown in FIGS. 18 and 19.

Metal-injecting system

The metal-injecting system (FIGS. 3, 4 and 5) consists of a conventional melting pot 214 having a pressurizing chamber 220 (FIG. 3) mounted in the bottom thereof. A pressurizing piston 222 is mounted for reciprocation into and out of the pressure pot 220 by means of an upright tubular housing 224. A double acting air cylinder 226 is connected to the piston 222 for reciprocating the same in response to air pressure admitted to the cylinder 226.

Intermediate the ends of the piston 222 is a lever 228 pivotally mounted between the ends thereof about a pin 230 fixedly mounted to the stationary machine frame. The end 232 of this lever fits into a companion slot in the piston 222 and also passes through a slot in the guiding cylinder 224. Thus, when the lever 228 is held in the position as shown in FIG. 3, the piston 222 is prevented from operating (protracting).

The outer end of the lever 228 is provided with a roller 234 which is engaged, as shown in FIG. 3, normally by an upwardly inclined safety cam 236. This safety cam 236 is secured to the left-hand (FIG. 3) end of the reciprocating bar 170 so as to engage normally the roller 234 to prevent the lever 228 from swinging. When the reciprocating bar 170 is retracted by moving toward the right in FIG. 3, the safety cam 236 is withdrawn from the roller 234, permitting the same end of the lever 228 to rise. This permits the piston 222 to depress for pumping molten lead out of the pressurizing chamber 220 up through the gate 210 and into the mold cavity via the sprue hole 88. This metal injecting system may be the same as that used in the apparatus covered by Pouell Patent No. 2,821,756.

The purpose of the safety cam 236 is to prevent the piston 222 from being actuated except at the proper moment in the operating cycle of the entire machine.

Clip-feeding mechanism

The clip-feeding mechanism is illustrated by FIGS. 21-36 inclusive. As shown in FIG. 26, this mechanism comprises generally a vibrating-clip feeder 240, an inclined slide 242 and a horizontal conveyor 244. The vibrating-clip feeder 240 is of conventional construction and is manufactured by the Vibromatic Co., Inc. of Noblesville, Indiana. The vibrating motor used in conjunction with the feeder is manufactured by Syntron Company of Homer City, Pennsylvania, and is of conventional construction. This feeder 240 is illustrated in detail in FIGS. 34, 35 and 36.

Referring to FIGS. 21, 22 and 23, the horizontal clip conveyor 244 comprises a stationary bed 246 made of a length of flat strip steel, which is securely fastened to the machine frame. The left-hand end of the bed 246 as viewed in FIG. 21 terminates immediately adjacent to the plunger 130 and extends horizontally away therefrom. On this bed 246 is mounted for longitudinal sliding movement two T-section rails 248 and 250 in tandem as shown in FIG. 24. As shown in FIGS. 28 and 29, the rail 250 extends to a point beneath the inclined slide 242.

Also slidably mounted on the bed 246 is an elongated bar 252 (FIG. 21) which slides longitudinally in a way provided by a gib rail 254 which is fixedly secured to the bed 246. The bar 252 is also bolted to the rail 250 but not to the rail 248. Thus, the bar slide 252 and the rail 250 slide longitudinally as a single unit on the bed 246.

A side plate 256 secured to the bed 246 on the side opposite the gib rail 254 provides a way 258 (FIG. 23) in which the rails 248 and 250 can slide longitudinally. It is important that the movement of the two rails 248 and 250 be limited to rectilinear, sliding movement.

Intermediate the ends of the T-section rail 250 and mounted on the stationary side plate 256 is mounted a block 260 (FIG. 22) which carries a wedge-shaped detent 262. This detent 262 is mounted for reciprocation vertically and is biased downwardly by means of a compression spring 264. The detent 262 is also positioned immediately above the stem of the rail 250 with the point thereof being urged into operative engagement with the rail. Since the block 260 is mounted on the side plate 256, the rail 250 will reciprocate relative thereto.

The purpose of this detent 262 is to prevent rightward movement of clips 50 on the rail 250 but on the other hand to permit leftward movement thereof with the rail. This will be explained in more detail later on.

As shown in FIG. 23, the bed 246 is provided with a longitudinally extending slot 266 which receives an extension 268 attached to the slide bar 252. Then, clamped to the extension 268 is one end of an operating lever 270 which will be described in more detail later on. The slot 266 is long enough to permit longitudinal sliding movement of the slide bar 252 in an amount which fulfills certain requirements as will be delineated later on.

In the right-hand end of the slide bar 252 as viewed in FIGS. 21, 24 and 28 is provided another detent 272 wedge-shaped as shown, which extends laterally from a socket in the slide bar 252 to engage the side of the stem of the rail 250. A compression spring 274 in the socket receives the detent 272 which yieldably urges the latter outwardly into engagement with the rail 250. The inclination of the detent is such as to prevent clips 50 from moving toward the right (FIG. 28) with respect to the slide bar 252. On the other hand, the inclination is such as to permit movement of a clip leftwardly on the rail 250. The detent 272 is positioned such that when the rail 250 is fully retracted to the position as illustrated in FIGS. 28 and 29, it will be positioned to the rear of a clip stop 276 (FIG. 29), which is contiguous with the top edge of the rail 250 and is stationary. This stop 276 prevents rightward movement of a clip on rail 250. Thus, when the bar slide 252 moves forwardly in the direction

of the arrow "F" (FIG. 28), the detent 272 will engage and carry with it clips 50 that are on the rail 250.

The front rail 248 is provided with a longitudinally extending slot 278 (FIGS. 24 and 25). An upstanding pin 280 on the bed 246 just enters the slot 278 and thereby limits the distance which the rail 248 can reciprocate.

On the opposite side of the rail 248 is provided a slot 282 (FIG. 24) which receives a pin 284 extending laterally from the slide bar 252. Engagement of the pin 284 with the right-hand end of the slot 282 when the slide 252 is moving in the reverse direction "R" (FIG. 24) results in corresponding reverse movement of the rail 248 with, however, a gap 286 being developed between the two rails 248 and 250. The pin 280 in the slot 272 prevents the rail 248 from moving in a rightward direction (FIG. 24) beyond the point at which the end of the slot 278 is engaged. The purpose of providing this relative movement between the two rails 248 and 250 will be explained more fully hereinafter.

Referring once again to FIGS. 21 and 24, a supporting block 288 is mounted on the right-hand end of the bed 246 so as to be stationary. Mounted in this block 288 for lateral reciprocation is a plunger 290 having a rectangular notch 292 formed therein. As shown in FIG. 24, this notch 292 straddles the rail 250 as well as the inclined rail 294 of the inclined slide 242. The plunger 290 is spring-biased laterally, as viewed in FIG. 24, by three compression springs 296 mounted in the block 288, these compression springs normally urging the lower edge of the notch 292 as viewed in FIG. 24 into contact with the side of the inclined rail 294.

A cam block 298 mounted on the slide bar 252 near the right-hand end thereof is provided with a longitudinally extending cam surface 300 which is normally engaged (FIG. 24) by the distal end of the plunger 290. In this position, the lower edge of the notch 292 as viewed in FIG. 24 engages the side of the inclined rail 294. When the slide bar 252 moves forwardly in the direction of the arrow F (FIG. 28), it carries with it the cam block 298. The camming surface 300 moves relative to the plunger 290, thereby moving the latter into the block 288 (FIG. 24) when engaged by the land portion 302 of the camming surface 300. When so engaged the plunger 290 releases from the slide rail 294 and permits clips 50 to slide down the rail 294 past the plunger 290 and onto the conveyor rail 250.

The inclined slide 242 comprises a bar of steel 304 (FIGS. 29, 30 and 32) which has the rail 294 machined along the upper edge thereof. The size and shape of this rail 294 is such as to receive clips 50 for sliding movement therealong. This bar 304 is rigidly secured to the conveyor bed 246 or to some other structure which will hold it stationary. The lower end of slide rail 294 (FIG. 29) terminates immediately adjacent to and in alignment with the stem of the T-section rail 250 (FIG. 29).

Near the upper end of the inclined supporting bar 304 (FIG. 32) is mounted a gib block 306 having a way 308 which receives a cam body 310 for reciprocation. This cam body 310 (FIGS. 30 and 32) mounts a cantilever 312 for pivotal movement about a pin 314, the upper side of this lever 312 being engageable with the plunger of a microswitch 316 mounted on the cam body 310. The distal end 318 of the lever 312 is slightly curved so as to ride upwardly over a riser rail 320 (FIG. 31) thereby swinging the lever 312 clockwise as viewed in FIG. 30. The lever 312 is also provided with a detent lobe 322 which normally engages the top edge of the rail 294. The purpose of the lobe 322 is to engage clips 50 and prevent them from moving on the rail 294 and also to actuate the microswitch 316. However, when the cam block 310 moves forwardly in the direction of the arrow "F" (FIG. 30) to a point at which the lever end 318 rides onto the riser 320, the lobe 322 is lifted out of engagement with the clip 50 so as to permit it and others to gravitate

Whenever a clip 50 is positioned between the lobe 322 and the rail 294, the microswitch 316 is actuated in a direction to permit the total machinery to operate properly. If, however, a clip is absent under the lobe 322, the microswitch is deactivated to stop the machine. By this means, the proper feeding of clips to the machine is assured at all times during machine operation.

On the front end of the block 310 (FIG. 30) is mounted a depressor finger 324 which normally engages a pin 326 spring-biased upwardly in a block 328 secured to the 10 supporting bar 304. The lower end of the pin 326 extends downwardly into a notch 330 formed in the rail 294 such that whenever a clip 50 is present underneath the pin 326 on the rail 294, movement of the depressor finger 324 over the pin 326 depresses the latter and forces the clip 50 down into the notch 330. This prevents the clip 50 from backing upwardly (moving toward the right) as viewed in FIG. 30.

A pitman 332 connects the sliding block 310 to the cam block 298 (FIGS. 21, 24) whereby reciprocatory motion of the block 298 may be transferred to the block 310. The mechanism is so dimensioned that when the slide bar 252 is protracted to its fullest extent (moved leftwardly in FIG. 21), the block 310 will be moved downwardly on the supporting bar 304 to a point at which the depressor finger 324 engages the pin 326 and the end 318 of the lever 312 rides up over the riser 320.

The rail 294 is so dimensioned as to permit the clips 50 to gravitate downwardly in sequence.

Referring now to FIGS. 30a and 30b, a detouring device generally indicated by the reference numeral 334 fastened to the upper end of the supporting bar 304 serves to derail clips on the rail 294 which are not properly positioned. As noted in FIG. 30a, the clips 50 have one leg 50a which is longer than the other leg 50b, and it is important in the operation of the present invention that the longer leg 50a be on the proper side of the various rails 294, 250 and 248 when they are fed to the plunger 130. This derailing device is composed of a block 336 secured to one side 338 of the supporting bar 304 and has one edge immediately adjacent to the side 340 of the rail 294. The top of the block 336 is inclined as indicated by the numeral 342. Immediately adjacent to this inclined edge 342, the block 336 is slotted at 344 to an extent as shown in FIG. 30b. Immediately over the rail 294 and in longitudinal alignment therewith, the block 336 is machined to provide an overhead riser 346, this riser being spaced above the rail 294 to permit the passage of clips 50 therebeneath.

When a clip 50 on the rail 294 is reversed and is approaching the block 336, the longer side 50a rides onto an inclined surface 348 on the block 336 in registry with the slot 344 such that the clip 50 rises over the leading edge of the riser 346 and progresses onwardly to fall therefrom as shown by the dashed clip configurations 50c of FIG. 30a. If the clip is properly positioned on the rail 294 as indicated by the uppermost clip in FIG. 30a, the leg 50b is so short that it will not engage the inclined surface 348 and thereby be led upwardly onto the riser 346. Instead, the clip will merely pass beneath the riser 346 and continue on its way down the rail 294.

The upper end of the slide 294 is suitably fastened to and in alignment with the delivery rail 350 of the vibrator 240. The vibrator 240 continuously supplies clips properly oriented to the rail 294 from which they gravitate in tandem down the rail 294. While the vibrator 240 is herein specified, it will appear as obvious to persons skilled in the art that the rail corresponding to rail 294 may extend for a relatively great distance and be slightly inclined. A relatively large supply of clips may be sequentially placed onto the rail which may be vibrated to cause the clips 50 to gravitate toward the machine and eventually onto the rail 294. This elongated supply rail would thus correspond to the hopper of the vibrator 240.

in which a large supply of clips is deposited for feeding upwardly onto the delivery rail 350.

Turning now to FIG. 27, the delivery end of the conveyor mechanism 244 will now be described. Like numerals indicate like parts.

As described earlier, the guide block 132 which carries the plunger 130 for vertical reciprocation is mounted on the gib block 64. The plunger 130 is aligned with the rectangular cutout 92 in the gib block 64 so as to receive the lower end of the plunger 130. In line with the left-hand edge of the cutout 92 is an abutment block 352 which is secured to the gib block 64. The distal end 354 of the T-rail 248 occupies a position in which it is perfectly aligned with the U-shaped recess 140 in the plunger. Thus, when the rail 248 is moved toward the left as viewed in FIGS. 21 and 27, the rail end 354 will pass in alignment through the recess 140 to a point just short of touching the abutment block 352. Actually, a clearance between the bottom of the recess 140 and the top of the rail 248 equal to the thickness of a clip 50 is provided such that when the rail end moves underneath the plunger recess 140, a clip 50 will be carried with it until the block 350 is abutted by the clip. At this time, the magnets 142 attract the clip 50 and hold the same in the recess 140 permitting the rail 248 to be retracted without the clip. The clip 50 is thus transferred to the recess 140, following which the plunger 130 may be depressed so as to carry the clip downwardly onto the clip-receiving lips 90 (FIG. 6).

To the stationary guide block 132 is secured another block 356 which carries a pair of detents 358 and 360, respectively, and a plunger 362. The detent 358 is spring-biased downwardly and is provided with a wedge-shaped head 364 which permits the clip 50 to be moved toward the left into the plunger recess 140 but prevents return of the clip from the recess. It should be noted at this point that the width of the plunger 130 at the recess 140 is exactly equal to the length of one clip 50, therefore the distance between the lateral edge 366 of the detent 358 and the abutment block 352 is exactly equal to the length of one clip 50.

The second detent 360 is wedge-shaped similarly to the detent 358 and is positioned with the side 368 thereof a distance from the detent 358 equal to the length of two clips 50. Immediately beneath the detent 360 with the rail 248 in the position illustrated in FIG. 27, the stem of the rail is relieved to provide a notch 370. This permits the detent 360 to always fall in behind the second clip 50d each time the rail 248 cycles to pass beneath the plunger 130.

In operation, with the plunger 130 elevated to its illustrated position and the rail 248 retracted as shown, leftward movement of the rail 248 will carry the three clips therewith until the endmost clip is positioned directly beneath and in registry with the plunger 130. The end 55 of the notch 370 forces the three clips to move in unison with the rail 248. When the rail 248 retracts to its illustrated position, the third clip 50e engages the detent 360 and is thereby prevented from moving in a rightward direction with the rail 248. This results in positioning the two clips 50d and 50e on the left-hand end where the two clips 50 and 50d are illustrated. Thus, it will be seen that as a clip is transferred from the rail 248 to the plunger 130, another clip advances on the rail 248 to replace the one delivered.

The operation of the clip-feeding mechanism will now be explained. In the starting position, the two rails 248 and 250 are retracted toward the right as far as possible, as illustrated in FIG. 24. FIGS. 28 and 29 show the position of the right-hand end of the rail 250 when in this fully retracted or starting position. In this position, the detent 272 (FIGS. 28 and 29) is positioned behind the endmost clip 50 which abuts against the stop 276 on the supporting bar 304. At this point it should be noted that the entire length of the two rails 248 and 250 is filled 70 with clips in tandem as clearly shown in FIG. 21.

In starting the feeding operation, the slide rail 252 is moved leftwardly as viewed in FIGS. 21 and 24 thereby carrying with it the rail 250 and the detent 272 (FIGS. 28 and 29). As shown in FIG. 24, the rail 250 will move forwardly the distance 286 (FIG. 24) before the rail 248 will be moved, since the rail 248 can move only by an abutting contact with the rail 250. Since the entire length of the two rails 248 and 250 is completely filled with clips, the initial relative movement between the rails 248 and 250 results in the clips being advanced along the rail 248 in synchronism with the motion of the rail 250. This results in projecting the endmost clip as seen in FIG. 27 leftwardly off the rail 248 slightly by the time the gap 286 between the two rails is taken up. Following this, continued leftward movement of the slide rail 252 carries both rails 248 and 250 therewith as well as all of the clips on the rails. This leftward movement is continued until the endmost clip of FIG. 27 abuts against the stop block 352 at which time the clip is properly positioned in the plunger 130. At this moment, leftward movement of the slide rail 252 ceases, whereupon the rightward stroke of the slide rail 252 is ready to begin.

It should be noted that it is necessary for the entire length of the rails 248 and 250 to be kept filled at all times with clips. This means, then, that as the rails deliver a clip to the plunger 130, this clip must be replaced by one from the inclined slide 242. This happens as shown in FIG. 21 with the advancement of the rails 248 and 250 to the transferring position beneath the plunger 130. As the rail 250 protracts, the clip 50f (FIG. 21, on the right-hand end of the rail 250) slides off the inclined slide 242 and falls in behind the detent 272 as shown. The sliding movement of the clip 50f from the slide 242 is permitted by reason of the fact that the plunger 288 has been released from the slide 242.

Now, when the slide bar 252 is started on its return stroke, only the rail 250 will start the return movement therewith. At this moment, the detent 262 (FIG. 21) falls behind the next adjacent clip 50 and prevents the entire row of clips on the left-hand side thereof as viewed in FIG. 21 from moving rightwardly therewith. However, the rail 250 continues to move rightwardly relative to all of the clips, since the endmost clip 50f engages the abutment 276 (FIG. 29). Thus, both the detent 262 as well as the end abutment 276 prevent rightward movement of the clips 50 with the rail 250. By reason of the inclined surface on the detent 272, it will ride up and over the endmost clip 50f until it eventually drops in behind as shown in FIGS. 28 and 29.

However, before the rail 250 is fully retracted, the pin 284 on the slide 252 picks up the front rail 248 and carries it rearwardly to the position illustrated in FIGS. 24 and 27. Since the full line of clips on the two rails 248 and 250 are held against rightward movement during the entire retractile motion of the two rails 248 and 250, when the rail retraction is completed, the clips will occupy the relative positions as illustrated in FIG. 27. Thus, the clips are in readiness for another transferring movement to the plunger 130.

The reason for dividing the delivery rail into two sections 248 and 250 for providing the gap 286 (FIG. 24) will now be explained.

In order for the detent 272 to be positioned in back of the clip 50f (FIGS. 28 and 29) on each complete stroke of the slide bar 252, it is necessary that the slide bar 252 and its rail 250 reciprocate a distance slightly longer than the length of each clip 50. This becomes evident from a comparison of FIGS. 21 and 29 in FIG. 21 the rail 250 is shown in its fully protracted position to position the detent 272 on the forward side of the rearmost clip 50f. Then, in FIGS. 28 and 29, the rail 250 is shown in its fully retracted position in which the detent 272 has traveled for the entire length of the clip 50f and an additional increment to position the detent

272 in behind the clip 50f. Thus, it will be apparent that the rail 250 must reciprocate for a distance slightly longer than an individual clip 50. For example, if a clip 50 is one inch long, the reciprocating travel of the rail 250 may be about 1½ inches.

While it is necessary for the rail 250 to travel this given distance, it will at once become apparent that the front rail 248 cannot travel as far because if this were true it would be moved past the abutment block 352 in FIG. 27. Thus, it is necessary for the rail 248 to travel a shorter distance than the rail 250. This is effected by reason of the gap 286 (FIG. 24) whereby the rail 250 can move about ⅓ of an inch before the rail 248 is moved. Thus, while the rail 250 is being reciprocated 15 1½ inches, the rail 248 is reciprocated only about ⅓ to one inch. This results in precisely feeding clips to the plunger 130 in sequence and maintains the two rails 248 and 250 full of clips at all times.

Actuating mechanism

The actuating mechanism is illustrated in at least FIGS. 4, 5 and 37-42 inclusive. As shown more clearly in FIG. 5, a cam box generally indicated by the reference numeral 370 having two walls 372 and 374 fixedly secured 20 to the machine frame sides 54 has mounted for rotation therein a barrel cam 376 as clearly shown in FIGS. 4, 5 and 42. The barrel cam 376 is shown in detail in FIGS. 37, 38 and 39. The barrel cam 376 rotates on an axis which extends in the direction parallel to the direction 25 of sliding movement of the carrier plate 58 and the reciprocating bar 170 as shown in FIG. 5. On the top edges of the two side plates 372 and 374 are mounted, respectively, two gib rails 378 which receive for sliding movement the cam plate 380, the gib rails 378 guiding the cam 30 plate 380 for reciprocatory movement in a direction parallel to that of the carrier plate 58. A splicing block 382 rigidly connects the two plates 380 and 58 together for synchronous sliding movement.

A cam follower 384 mounted on the cam plate 382 35 depends into a camming groove 386 in the barrel cam 376 as shown more clearly in FIGS. 4 and 42. The shape of this cam groove 386 will be described more fully hereinafter.

The reciprocating bar 170 has a bar slide 388 connected 40 to the right-hand end thereof as shown more clearly in FIG. 5 which carries a cam follower 390 engaged with the circumferential cam groove 392 in the barrel cam 376. The side plate 374 is longitudinally slotted to receive the bar slide 388 such that the reciprocating bar 170 45 as well as the bar slide 388 may move in unison in a direction parallel to the sliding movement of the two plates 380 and 58. The precise shape of the cam groove 392 in the barrel cam 376 will be explained in detail hereinafter.

In the left-hand end of the barrel cam 376 as viewed in FIG. 4 is provided a cam groove 394 as shown more clearly in FIGS. 37 and 38. This cam groove 394 is not shown in FIG. 4. A reciprocable slide bar 396 is mounted in the side 372 and carries a follower 398 on the end 50 thereof which enters the end groove 394. The outer end of this bar 396 is connected to the end 400 of the lever 270 which is mounted for swinging movement about an upright axis on a pivot block 402. The pivot block 402 is mounted on a slide 404 carried in a way 55 406. The direction of sliding movement in the way 406 is substantially parallel to the movement of the two plates 58 and 380. Thus, as the bar 396 (FIG. 38) is reciprocated by the pear-shaped cam groove 394, the lever 270 will be swung about its pivot 402 in moving the 60 slide bar 252 of the feeding mechanism 244.

Mounted on the left-hand end of the side plate 54 as viewed in FIG. 4 and as shown in FIGS. 38 and 29 is a microswitch 408 which is operated by a wedge-shaped cam 410 mounted for reciprocation in a casing 412. Projecting from the wedge-shaped cam 410 is a finger 414

which is yieldably urged into engagement with the periphery of the barrel cam 376 by means of a spring 416. The wedge-shaped cam 410 actuates the switch 408 in response to reciprocatory movement thereof. This reciprocatory movement is imparted to the cam 410 by means of two part-circumferential grooves 418 and 420 in the circumference of the barrel cam 376, the finger 414 riding into and out of these grooves 418 and 420 in response to rotation of the barrel cam 376. The grooves 418 and 420 thereupon cause corresponding opening and closing of the microswitch 408.

Another microswitch 422 is fastened to the side plate 372 (FIG. 5) and is equipped with a plunger 424 (FIG. 39) which extends through an opening in the side plate 372 to enter a part circumferential groove 426 in the barrel cam 376. The switch 422 is therefore opened and closed in response to the plunger 424 riding into and out of the groove 426.

As shown more clearly in FIG. 42, the microswitch 422 is connected in an electrical circuit which operates an air valve 428. This air valve 428 in turn is connected to the power cylinder 226 on the lead pump 224.

The microswitch 408 is connected in an electrical circuit to a second air valve 430 which in turn is connected to the double-acting air cylinder 186. Both of the air valves 428 and 430 are connected to a common source of air pressure 432. Actuation of the two switches 408 and 422 serves in the operation of the two air valves 428 and 430, respectively, whereby the two cylinders 226 and 186 are respectively operated. The sequence and manner of operation will be explained more fully hereinafter.

The particular shapes of the various grooves and recesses in the barrel cam 376 will now be described. In this connection, reference is made to FIGS. 37-41 inclusive, wherein the barrel cam 376 is shown in its actual form and as geometrically developed.

The two grooves 386 and 392 extend around the entire circumference of the barrel cam 376 as shown. The shallow grooves 418, 420 and 426 extend only part way around the circumferential extent of the barrel cam 376.

The peripheral surface of the barrel cam 376 is developed in FIG. 40 so as to show the particular shapes and relative positions of the various cam grooves. The peripheral surface of the barrel cam is laid out into a flat plane which is shown as being calibrated in degrees from zero to 360. FIG. 41 is a development of the end of the barrel cam 376 containing the pear-shaped groove 394, this development also being calibrated in degrees and positioned in precise operative alignment with the calibration of FIG. 40.

In order to establish the zero degree reference point in the two FIGS. 40 and 41 with the actual machine, reference is made to FIGS. 5 and 26 where the reference numeral 434 indicates an indexing or starting point with respect to which the degrees of revolution of the barrel cam 376 may be measured. Therefore, when it is stated that the barrel cam 376 is positioned for the starting of machine operation, the zero degree reference point in FIGS. 40 and 41 for the barrel cam 376 should be considered as being aligned with the index 434 as shown in FIGS. 5 and 26.

Now referring to FIG. 40 and considering only the cam groove 386, it will be noted that it is straight with the exception of a V-shaped deviation 436 which extends between the 315° and 45° portions of the drum.

For the groove 392, it is straight with the exception of a V-shaped deviation 438 which extends from the 330° to the 60° marks, respectively.

The groove 420 extends between the 75° and 90° marks, while the groove 418 extends between approximately 130° and 240°. The groove 426 extends from approximately 140° to 180°.

The end groove 394 as shown in FIG. 41 is straight with the exception of the V-shaped portion 440 which extends from approximately 245° to 45°, respectively.

In the starting of machine operation, the barrel cam 376 with its followers and plungers will be positioned with respect to each other as shown in FIGS. 40 and 41. In other words, FIGS. 40 and 41 show the various followers 384, 390, 398, 414, and 424 as being in the position at which machine operation is considered to be started.

Explanation of operation

For each revolution of the barrel cam 376 the machine will be operated through a complete cycle to fabricate one wheel balance weight as shown in FIGS. 1 and 2. Thus, in explaining the operation of the machine, a complete fabricating cycle from the beginning to end as governed by rotation of the barrel cam 376 from zero degrees to 360 degrees will be explained.

When the barrel cam 376 is positioned with its zero degree mark (FIGS. 40 and 41) in alignment with the index 434 (FIGS. 5 and 26), the various machine parts will be positioned as follows:

The carrier 58 will be fully retracted to the position illustrated in FIGS. 5 and 6 and the mold sections 72 and 74 will be completely separated; the plunger 130 will be elevated to the positions shown in FIGS. 21, 26, 27 and 42, and the power cylinder 186 will be retracted to withdraw the shear head 192 (FIGS. 16-19 inclusive) upwardly out of the path of the plunger 130; the reciprocating bar 170 will be in position as illustrated in FIG. 3, thereby preventing actuation of the lead pump piston 222; and the clip-feeding mechanism will be fully retracted to the position as shown in FIG. 24. Also at this starting, it is assumed that the pot 214 is filled with molten lead at the correct temperature.

The barrel cam rotates in a counterclockwise direction as viewed from the front of the machine, the front being the right-hand end of the machine as viewed in FIG. 5. This counterclockwise direction of rotation is indicated by the two arrows "X" in FIGS. 40 and 41. One more condition remains in the starting of machine operation for fabricating a weight and that involves the positioning of a clip 50 in the recess 140 of the plunger 130.

When the barrel cam 376 is rotated from zero degrees to approximately 40°, the mold sections 72 and 74 are first closed completely onto each other by the protractile movement of the carrier plate 58. When the front die block 116 is about $\frac{1}{8}$ inch short of fully closing onto the engaged sections 72 and 74, the depressor cam 148 moves the plunger 130 downwardly, thereby placing the clip 50 over the clip-receiving lips 90 on the mold sections 72 and 74. Then for the next five degrees of rotation of the barrel cam, the carrier plate 58 moves forwardly until the front die section 116 fully closes onto the engaged mold sections 72 and 74 thereby forming the die cavity 442 as shown in FIG. 17. Immediately upon the plunger 130 being fully depressed to place a clip over the lips 90 of the mold sections, the plunger 414 is operated by the groove 418 in the barrel cam 376 to actuate the microswitch 408 (FIG. 42) which in turn operates the air valve 430 to actuate the air cylinder 186. This results in the shear head 192 being protracted to the position as shown in FIG. 17 to engage the lower end of the plunger 130, holding the latter downwardly onto the lips 90 of the mold sections 72 and 74. The shear head 192 is held in this position from forty degrees to 150° rotation of the barrel cam.

At 50° rotation, the lead pump cylinder 226 is actuated by microswitch plunger 424 engaging the cam groove 426. Simultaneously with the actuation of the lead cylinder 226, the safety cam 236 (FIG. 3) is withdrawn rearwardly from the roller 234 by means of the V-shaped portion 438 of the cam groove 390 (FIG. 40). This permits the lead pump to cycle, forcing the piston 222 (FIG. 3) downwardly so as to inject lead through the conduit 210 (FIG. 16), the sprue hole 88 and into the die cavity 442. As seen in FIG. 16, the longer leg of the clip 50 is positioned inside the die cavity 442 so that the lead will flow

thereabout. The lead pump is actuated from about 50° to 90° rotation of the barrel cam, during which period of revolution the safety cam 236 is withdrawn from the pumping lever 228 by the reciprocating bar 388, 170.

From the points of 90° to 120° rotation, no parts of the machine are being actuated, thereby permitting the molten lead in the cavity 442 to cool.

From 120° to 155° rotation, the reciprocating bar 170 is moved forwardly to position the safety cam 236 over the roller 234, and the cross slide 146 (FIGS. 12 and 20) is traversed sideways to release from the plunger 130. At about 150° to 155°, the groove 418 leaves the microswitch plunger 414, thereby operating the latter to deactivate the cylinder 186. This withdraws the shear head 192 upwardly out of engagement with the lower end of the plunger 130. The plunger 130 thereupon immediately rises under the influence of the spring 140 (FIG. 16). Then between about the angle of 155° to 310°, the clip-feeding mechanism of FIG. 21 is actuated to deliver a clip to the plunger 130: in completing this cycle the feeding mechanism completely retracts from the plunger 130.

For the angle 315° to 360°, the mold 72, 74, 116 opens progressively by the carrier plate 58 retracting rearwardly. However, at about the angle of 345°, the cam groove 420 operates the microswitch 408 which in turn actuates the air cylinder 186 forcing the shear head 192 (FIGS. 16 through 19) downwardly between the separated mold sections 72 and 74 to sever the sprue. It is important to note that at the angle of 345° rotation of the barrel cam, the cam rollers 96 are registered with the straight portion 106 (FIG. 12) of the carrier plate 58 in which position the mold sections 72 and 74 are only partially opened. In this partial opened or separated condition, the clip 50 with the solidified lead thereon is still hanging over the lips 90. If the clips 50 are one inch long, it may be assumed that the mold sections 72 and 74 have separated only 1/2 inch, thereby leaving a quarter inch of each end of the clip overlapping the two lips 90. At this precise moment, when the cam rollers 96 are engaged with the straight portion 106 of the camming groove, the shear head 192 is actuated by the groove 420 (FIG. 40) moving through the sprue 88 shearing the same from the lead weight at the juncture with the weight and also from the conduit 210 at the mouth 218 thereof. Continued protractile movement of the shear head 192 results in the ejecting pin 202 knocking the weight off the mold sections 72 and 74 and down the inclined surface 66 of the inclined plate 60. At about the 360° mark, the cylinder 186 is deactivated to retract the shear head 192. Thus, at the 360° position, the mold sections 72, 74, 116 are completely opened, the safety cam 236 is engaged with the roller 234, the plunger 130 is elevated with the clip being in recess 140, the shear head 192 is fully retracted, and the machine is ready to complete another cycle of operation.

Recapitulating briefly the automatic operation of the machine, the pear-shaped cam groove 394 (FIG. 41) in the end of the barrel shaped cam 376 operates to swing the lever 270 about its pivot 402. This swinging movement is adjusted such as to reciprocate the slide rail 252 (FIG. 24) of the clip-feeding mechanism the proper distance. Thus, with each complete revolution of the barrel cam 376, the slide rail 252 (FIGS. 21 and 24) will be reciprocated once.

The cam groove 386 in the barrel cam serves to reciprocate the plates 380 and 58 in their respective gibs once for each revolution of the barrel cam. The reciprocating bar 170, 388 with its follower 390 engaged with the barrel cam groove 392 is also reciprocated once for each revolution of the barrel cam.

For each revolution of the barrel cam 376, the air cylinder 186 is actuated twice, the first time for holding the plunger 130 downwardly and into snug engagement with the clip 50 as it is being held onto the mold section lips 70

90 and the second time when it is actuated to shear off the sprue 88 and to knock out the finished weight.

The lead pump 226 is actuated once for each revolution of the barrel cam 376 by the shallow groove 426.

When the barrel cam 376 is rotated to the point where its zero degree mark coincides with the index 434 (FIGS. 5 and 26), the follower 384 is also in line with this zero degree mark, but the follower 390 is at the 270° mark while the two microswitch plungers 414 and 424 are at the 90° mark. Simultaneously, the follower 398 in the end groove 394 is at the 90° mark.

A simplified chart of the machine operation is given in the following with the various phases of machine operation being related to the extent of rotation of the barrel cam 376.

Rotation of drum 376

Degrees:

0°—

- (a) Mold 72, 74, 116 fully open with rollers 96 in groove portion 104.
- (b) Plunger 130 elevated and supplied with a clip 50.
- (c) Rails 248 and 250 fully retracted.
- (d) Sprue-shearing cylinder 186 fully retracted.
- (e) Safety cam 236 engaged with lead pump handle 228; lead cylinder 226 fully retracted.

From 0°—40°—

- (a) Rear mold sections 72 and 74 are closed by advancing carrier 58 to a point at which cam groove portions 108 engages rollers 96, 98 just short of the end of groove 108. In this position, die section 116 is just short of closing onto 72, 74.

From 40°—150°—

- (a) Plunger 130 is fully depressed initially by the depressor cam 148 to position a clip 50 over lips 90 of die 72, 74.
- (b) Cylinder 186 actuated to protract head 192 onto plunger 130 to latch the latter in its depressed position. (FIGS. 16—19.)

From 40°—45°—

- (a) Front die section 116 fully closes onto engaged mold sections 72 and 74 after plunger 130 has placed a clip over lips 90.

From 50°—90°—

- (a) Bar 170 is retracted to withdraw safety cam 236 from pump handle 228.
- (b) Microswitch 422 operates to actuate pump cylinder 226 which injects molten lead into die cavity. Metal starts solidifying.

90°—

- (a) Pump cylinder 226 deactivated.

From 90°—120°—

- (a) Bar 170 is stationary as retracted with safety cam 246 withdrawn from pump handle 228.

- (b) Depressor cam 148 is stationary holding plunger 130 down.

From 120°—155°—

- (a) Bar 170 protracts moving safety cam 236 over roller 234.

- (b) Cross slide 146 traversed outwardly out of engagement with plunger 130 by the cam 160, 162 which protracts with bar 170.

155°—

- (a) Cylinder 186 deactivated retracting head 192 out of latching engagement with plunger 130; the plunger 130 now snaps upwardly under force of spring 140.

From 155°—245°—

- (a) Feed rails 248, 250 protract beneath plunger 130 to deposit a clip 50 into recess 140 (FIG. 21).

From 245°—310°—

- (a) Feed rails 248, 250 retract from beneath

plunger 130 leaving a clip 50 in the recess 140.
From 315°-345°—

(a) Carrier 58 partially retracts withdrawing die section 116 from mold sections 72 and 74 which separate partially to the position at which rollers 96 and 98 register with the dwell surface 106 in the cam slot 100 (FIG. 12).

345°—

- (a) Switch 408 is operated which actuates power cylinder 186 which protracts shear head 192 to shear off sprue 88 between surfaces 82 and 84 of mold sections.
- (b) Clip 50 of molded weight remains on lips 90 (FIG. 6) during this shearing operation.
- (c) Finished weight is knocked down incline 66 by ejecting pin 202 (FIG. 19).

From 345°-360°—

- (a) Power cylinder 186 is deactuated to retract head 192.
- (b) Mold 72, 74, 116 opens fully.
- (c) Cross-slide 146 traverses inwardly under spring 156 force and cam 178.

While I have described specific embodiments of my invention, further modifications and improvements will occur to those skilled in the art and I desire therefore in the appended claims to cover all modifications which do not depart from the spirit and scope of this invention.

What is claimed is:

1. Die casting apparatus comprising in combination a support, a single die mounted on said support and having a recess therein, said die being divided into two mold sections having abutting surfaces, means mounting said mold sections for movement in a first rectilinear direction toward each other to engage said abutting surfaces and then away from each other to disengage said abutting surfaces, a sprue hole passing through said single die in registry with said abutting surfaces when engaged, one portion of said hole being in one surface and the other portion being in the other surface, one portion of said recess being in one mold section and the other portion thereof being in the other mold section, a movable die mounted on said support for movement in a direction transverse to said first direction selectively into and out of engagement with said single die, said movable die having a recess therein, said single and movable dies having engageable surfaces which surround a die cavity formed by the recesses therein, a sprue-shearing device mounted on said support and having a reciprocable shear head thereon which moves in the space between said abutting surfaces when said mold sections are parted, means for moving said mold sections into engagement with each other and said movable die into engagement with said single die formed by the engaged mold sections, injection means for injecting molten metal through said space hole into said die cavity, means for separating said mold sections and movable die from each other after said metal has hardened, said shear head having sprue-cutting means movable to a position contiguous with a portion of the wall of said cavity and a portion of said injection means, and means for actuating said sprue-shearing device to move said shear head between the separated abutting surfaces for shearing off the sprue formed by said sprue hole.

2. For use in die casting apparatus, a clip-transferring mechanism comprising a support, a member mounted on said support for rectilinear movement between two opposite positions, holding means on said member and movable to said opposite positions for releasably holding a clip, a die mounted on said support, said die having a cavity and a clip-receiving portion adjacent to said cavity, said die being positioned with respect to said member such that said clip-receiving portion substantially coincides with one of said opposite positions of said

holding means, whereby a clip held by said holding means may be transferred from the other of said positions to said clip-receiving portion, means for moving clips sequentially to said holding means when the latter is in said other position, means for injecting material into said cavity, and means for retaining said holding means in said one position while said material is being injected into said cavity.

3. For use in a die casting apparatus, a clip-transferring mechanism comprising a support, a guide carried by said support and having a plunger reciprocably mounted thereon, said plunger having an end provided with a U-shaped recess, at least one magnet secured to said end adjacent to said recess whereby a U-shaped clip may be positioned in said recess and held therein by said magnet, means providing a stop in operative registry with said recess, and means for moving clips sequentially into engagement with said stop and into registry with said recess.

4. For use in die casting apparatus, a clip-feeding mechanism comprising a bed having an elongated way thereon, an elongated T-section rail reciprocably mounted in said way with the T-section being inverted, an actuator mounted on said bed for reciprocation in a direction parallel to said rail, said actuator being connected to said rail, a detent mounted on said actuator, means yieldably urging said detent into operative engagement with one side of the stem of said rail, and a stationary abutment on said bed near one end of said rail and contiguous to said stem, whereby U-shaped clips on said stem engage said abutment permitting movement of said rail relative to said clips.

5. For use in die casting apparatus, a clip-feeding mechanism comprising a bed having an elongated way thereon, an elongated T-section rail reciprocably mounted in said way with the T-section being inverted, an actuator mounted on said bed for reciprocation in a direction parallel to said rail, said actuator being connected to said rail, a detent mounted on said actuator, means yieldably urging said detent into operative engagement with one side of the stem of said rail, a stationary abutment on said bed near one end of said rail and contiguous to said stem, and an inclined inverted T-section rail extending longitudinally in line with the first-mentioned rail beyond said one end, said inclined rail merging with said one end and being inclined upwardly and away therefrom.

6. The clip-feeding mechanism of claim 5 including in combination a member movably mounted on said bed and operatively engaging the lower end of said inclined T-section rail, cam means operatively connected to said actuator for releasing said member from said inclined rail when the first-mentioned actuator is moved in a direction away from said abutment.

7. For use in die casting apparatus, a clip-feeding mechanism comprising a bed having an elongated way thereon, two elongated longitudinally aligned T-section rails mounted in inverted position in said way for reciprocal movement, adjacent ends of said rails being engageable, lost-motion connection means connecting one of said rails to the other rail to provide limited relative separation movement of said rails, actuating means on said bed connected to one of said rails for imparting alternative reciprocatory movement to said rails, first detent means on said bed yieldably urged into operative engagement with said one rail, second detent means carried by said actuating means and yieldably urged into operative engagement with said one rail, and means moving said second detent means in unison with said one rail.

8. In combination with the clip-feeding mechanism of claim 7, a clip-transferring mechanism comprising a guide carried by said bed and having a plunger reciprocably mounted thereon, said guide being positioned just beyond but adjacent to the distal end of said other rail, a stopping block on said bed and spaced opposite said distal

end, said plunger having an end movable between said block and said distal end, said plunger end having a U-shaped recess, at least one magnet mounted in said recess, said plunger having one operative position which locates said recess immediately above said other rail when the latter is moved longitudinally, control means operatively connected to said actuating means and to said plunger for first moving said distal end toward said stopping block and into operative engagement with said recess and for secondly retracting said distal end from said recess and then protracting said plunger to a second operative position.

9. The clip-feeding mechanism of claim 7 but including in combination means on said bed for holding stationary a series of U-shaped clips on said other rail while the latter moves longitudinally in one direction.

10. For use in die casting apparatus, a clip-transferring mechanism comprising a support, a member mounted on said support for movement between two opposite positions, means on said member for releasably holding a clip, a die mounted on said support, said die having a cavity and a clip-receiving portion adjacent to said cavity, said holding means on said member being operatively engageable with said clip-receiving portion when said member is moved to one of said opposite positions, whereby a clip held by said member may be transferred to said clip-receiving portion, means for clamping said holding means in operative engagement with said clip-receiving portion, and means for injecting molten material into said cavity while said holding means is clamped in operative engagement with said clip-receiving portion, whereby a clip on said clip-receiving portion is held in place during molding by said holding means.

11. For use in die casting apparatus for assembling U-shaped clips to a cast metal body, a support, a die mounted on said support, said die having a cavity and a clip-receiving portion adjacent to said cavity, a rail having a clip-carrying portion, said rail having opposite ends and being mounted on said support for movement between two opposite positions, one of said ends in one of said positions being adjacent to and aligned with said clip-receiving portion, said one end in the other of said positions being spaced away from and out of alignment with said clip-receiving portion, and means for sequentially feeding clips from said rail to said clip-receiving portion following movement of said one end from said one position toward said other position.

12. Die casting apparatus comprising in combination a support, a single die mounted on said support and having a recess therein, said die being divided into two mold sections having abutting surfaces, means mounting said mold sections for movement in a first rectilinear direction toward each other to engage said abutting surfaces and then away from each other to disengage said abutting surfaces, a sprue hole passing through said single die in registry with said abutting surfaces when engaged, one portion of said hole being in one surface and the other portion being in the other surface, one portion of said recess being in one mold section and the other portion thereof being in the other mold section, a movable die mounted on said support for movement in a direction transverse to said first direction selectively into and out of engagement with said single die, said movable die having a recess therein, said single and movable dies having engageable surfaces which surround a die cavity formed by the recesses therein, a sprue-shearing device mounted on said support and having a reciprocable shear head thereon which moves in the space between said abutting surfaces when said mold sections are parted, means for moving said mold sections into engagement with each other and said movable die into engagement with said single die formed by the engaged mold sections, injection means for injecting molten metal through said sprue hole into said die cavity, means for separating said mold sections and movable die from each

other after said metal has hardened, said shear head having sprue-cutting means movable to a position contiguous with a portion of the wall of said cavity and a portion of said injection means, means for actuating said sprue-shearing device to move said shear head between the separated abutting surfaces for shearing off the sprue formed by said sprue hole, a conduit mounted on said support, said conduit having an end and an opening therethrough which registers with said sprue hole when said mold sections are closed onto each other, said mold sections having a thickness dimension which separates said die cavity from said conduit end, said shear head having cutting edges separated by a distance equal to said thickness dimension, one of said cutting edges being contiguously movable across said conduit end and opening to shear a sprue therefrom and the other cutting edge being movable across the sprue at its juncture with the die cavity thereby severing the entire sprue formed in the sprue hole from both the conduit opening and the finished cast product.

13. The apparatus of claim 12 with said other cutting edge being positioned ahead of said one cutting edge whereby the sprue at the entrance to the cavity is severed in advance of severing the sprue at the conduit opening.

14. For use in die casting apparatus for fabricating wheel balance weights, a clip-feeding mechanism comprising supporting means, an elongated clip-supporting device movably mounted on said supporting means, means connected to said clip-supporting device for moving the latter longitudinally, means for moving clips carried by said device in unison therewith in one direction, and abutment means for stopping movement of said U-shaped clips for the opposite direction of movement of said device whereby said clip-supporting device may move in said opposite direction relative to said clips.

15. For use in die casting apparatus for fabricating wheel balance weights, a clip-feeding mechanism comprising supporting means, two elongated longitudinally aligned clip-supporting devices movably mounted on said supporting means, adjacent ends of said elongated devices being engageable, lost-motion connection means connecting one of said devices to the other of said devices to provide limited relative longitudinal separation movement of said devices, means for alternatively moving said devices in the same opposite directions longitudinally thereof, means movable with one of said devices for moving clips carried by said one device in unison with movement of the latter in one of said directions, and means on said supporting means for stopping movement of said clips when said one device moves in the opposite direction, whereby said one device can move relative to said clips.

16. For use in die casting apparatus for fabricating wheel balance weights, a clip-feeding mechanism comprising supporting means, an elongated clip-supporting device movably mounted on said supporting means, means connected to said clip-supporting device for moving the latter longitudinally, means for moving clips carried by said device in unison therewith in one direction, abutment means for stopping movement of said U-shaped clips for the opposite direction of movement of said device whereby said clip-supporting device may move in said opposite direction relative to said clips, said clip-supporting device having a delivering end which is movable between first and second extreme positions, said delivering end being movable to said first position when said device is moved in said one direction and to said second position when said device is moved in said opposite direction, means for removing a clip from said delivering end when the latter is in said first position, cavity means having a clip-receiving portion, and means including said removing means for applying the last-mentioned clip to said clip-receiving portion.

17. For use in die-casting apparatus for assembling U-shaped clips to a cast metal body, a support, a die

mounted on said support, said die having a cavity and a clip-receiving portion adjacent to said cavity, a clip-supporting device having a clip-carrying portion, said device being elongated and having opposite ends, said device being mounted on said support for movement between two opposite positions, one of said ends in one of said positions being adjacent to and aligned with said clip-receiving portion, said one end in the other of said positions being spaced away from and out of alignment with said clip-receiving portion, and means for sequentially feeding clips from said device to said clip-receiving portion following movement of said one end from said one position toward said other position.

18. The apparatus of claim 17 wherein said feeding means comprises a clip-holding element, means mounting said element on said support for movement between first and second positions wherein said first position is adjacent to said one end when the latter is in said one position and said second position is adjacent to said clip-receiving portion.

19. The apparatus of claim 17 wherein said feeding means comprises a guide which carries a plunger for reciprocation, said guide being mounted on said support in alignment with said clip-receiving portion, said plunger being reciprocable into and out of operative engagement with said clip-receiving portion.

20. For use in die casting apparatus for assembling U-shaped clips to a cast metal body, a support, a die mounted on said support, said die having a cavity and a clip-receiving portion adjacent to said cavity, a clip-carrying device mounted on said support for movement

between two opposite positions, one of said positions being adjacent to and aligned with said clip-receiving portion, the other position being spaced away from and out of alignment with said clip-receiving portion, and means for sequentially feeding clips from said device to said clip-receiving portion following movement of said device from said one position toward said other position.

21. The apparatus of claim 20 wherein said feeding means includes an element selectively movable through a predetermined path into and out of operative engagement with said clip-receiving portion, said one position of said clip-carrying device being within said path, said other position of said device being outside said path.

UNITED STATES PATENT OFFICE
CERTIFICATE OF CORRECTION

Patent No. 3,191,246

June 29, 1965

Harry E. Pouell

It is hereby certified that error appears in the above numbered patent requiring correction and that the said Letters Patent should read as corrected below.

Column 10, line 44, for "release" read -- releases --; column 13, line 69, after "29" insert -- wherein --; column 14, line 15, for "247" read -- 248 --; column 18, line 55, for "246" read -- 236 --; column 19, line 57, for "space" read -- spruce --.

Signed and sealed this 28th day of December 1965.
